UNITED STATES PATENT OFFICE.

OSCAR P. NYSTROM, OF HOLLAND, MICHIGAN, ASSIGNOR TO HOLLAND FURNACE COMPANY, OF HOLLAND, MICHIGAN, A CORPORATION OF MICHIGAN.

HUMIDIFIER ATTACHMENT.

Application filed February 24, 1925. Serial No. 11,081.

This invention relates to a humidifier attachment which may be applied to furnaces. The attachment is designed to be applied at the upper side of a front or forward extension to the ash pit casting being adapted for application to furnaces already installed and in use or, if it is desired, to furnaces which are being installed, though, preferably, for new furnaces the humidifier will 5 be made as an integral part of the ash pit casting in accordance with the disclosure of my pending application for patent, Serial No. 727,136, filed July 21, 1924.

It is a primary object and purpose of the 15 present invention to provide a separable humidifier attachment in the form of a shallow receptacle, which preferably though not necessarily, is divided transversely into a number of compartments having transverse ribs, 20 the bottom of the receptacle inclining downwardly and inwardly so that a limited quantity of water may be held in front of each transverse rib level with its upper edge overflowing the top thereof when more water is 25 added. The lowermost compartment of the receptacle is provided with a drainage opening near its uppermost portion and when the water reaches a certain level in the lowermost compartment any additional water is 30 drained through the drainage opening into the ash pit of the furnace. The water thus drained is absorbed by the ashes dampening the same, eliminating dust and moistening the air passing to the burning fuel, all of 35 which is of great advantage in furnace operation.

A still further object of the invention is to provide a means in conjunction with the drainage opening to the ash pit either with 40 the separable receptacle or the humidifier cast integral with the furnace ash pit whereby gases, which might pass through said opening from the ash pit to the space enclosed by the outer casing of the furnace, 45 are trapped and held from mixing with the air in such space. It is understood that the air within the space enclosed by the outer casing of the furnace is heated and passes to the several rooms of the house or other building heated by the furnace and this trapping of gas is desirable in order that it shall 50 not mix with the air going to rooms of a dwelling, office or the like.

A still further object of the invention is

to provide a humidifier, with or without the 55 cross ribs which divide it into compartments, which occupies very little space at the upper side of the forward extension to the ash pit and with a removal of the bulky water pan ordinarily used, this being of advantage in 60 eliminating all obstructions to free circulation of the heated air which is delivered from the furnace.

Various other objects and purposes than 65 those stated together with novel constructions for the attaining of the same will appear with an understanding of the invention had from the following description taken in connection with the accompanying drawings, 70 in which,—

Fig. 1 is a fragmentary vertical section through the lower forward portion of a furnace equipped with my invention.

Fig. 2 is a fragmentary horizontal section taken through the furnace in a plane above 75 the humidifier.

Fig. 3 is a perspective view of the separable humidifier receptacle or tray, showing the preferred form thereof used.

Fig. 4 is a fragmentary enlarged vertical 80 section through the trap which is formed as an integral part of the tray or receptacle construction.

Fig. 5 is a view similar to Fig. 4, illustrating a slightly different form of construction wherein the trap is provided by means of a separately cast element which may be applied to the water holding receptacle. 85

Fig. 6 is a view similar to Fig. 5 illustrating the application of the trap to a humidifier wherein its structure is formed integral with the top of the forward extension to the ash pit, and 90

Fig. 7 is a fragmentary enlarged vertical 95 section illustrative of a different form of gas trap which may be used, though that shown in Figs. 3 to 6 is a preferred construction.

Like reference characters refer to like parts in the different figures of the drawings. 100

The furnace, in its construction, includes an ash pit casting 1 above which is the fire pot casting supported by and resting on the ash pit casting with the usual furnace grate between. The ash pit casting at its front side is provided with a forward extension having spaced apart substantially vertical sides 3 connected at their upper edges by an 105

integral cross member or top, preferably formed with a relatively short horizontal forward section 4 from which a wider downwardly and inwardly inclined section 5 extends. In the construction of the ash pit an upwardly extending boss 6 is formed and the same is shown though it comprises no essential or necessary feature of the invention in any way, being in practice used as a means for connecting a hook support (not shown) for the rod used to operate the grate.

The inner heater structure of the furnace is surrounded by an outer enclosing casing spaced therefrom which includes a front plate 7 of cast metal and a sheet metal drum 7^a which completes the enclosure of the furnace. The cast metal plate 7 at the front is used for the mounting of the various furnace doors one of which, indicated at 8, is used at the front of the ash pit and through the opening normally closed by which the ashes may be removed from the ash pit.

On the upper side or top of the forward extension to the ash pit, comprising the sections 4 and 5, the humidifier tray construction of my invention is adapted to be placed. It is formed as a single casting having a bottom with sections 9 and 10 conforming to and lying directly over the sections 4 and 5 of the ash pit extension. At each side edge ribs 11 extend upwardly for short distances. These ribs are integral with and connected by an outer or front rib 12 curved to correspond to the curvature of the plate 7 and lying against the inner side thereof. At their inner ends ribs 11 are connected by a second curved rib 13 which normally is spaced a short distance from the walls of the fire pot casting 2.

40 The humidifier can be used with only the bottom and usual border ribs 11, 12 and 13 but I prefer to divide the space enclosed into compartments, casting cross ribs 14 and 15 integral with the tray to lie between the side ribs 11 thereof in spaced apart relation. An upwardly projecting ring 16 is formed with the tray for the reception of the boss 6 heretofore described. The tray when placed on the top of the ash pit extension is located properly in position by the boss 6 passing through the ring 16. In addition an opening 17 is made in the section 5 of the top from which a groove 18, formed in the under side of said section 5, extends downwardly to the inner edge of the top of the ash pit extension. And a lug 19 with an opening 20 therethrough is connected with and extends downwardly from the bottom section 10 of the tray, being adapted to enter the opening 17 and aid in the proper positioning of the water holding tray or receptacle on the ash pit front extension. The lug 19 with the opening 20 therethrough is positioned so that said opening lies directly back of the lower cross rib 15 and at an uppermost point

of the lower compartment of the tray or receptacle.

It is evident that after water is delivered to the front receptacle of the tray between the front rib 12 and the front cross rib 14, as the upper edge of the rib 14 lies in a plane lower than the upper edges of the side ribs 11 and the front rib 12, when this compartment has been filled to the level of the upper edge of the cross rib 14, it overflows into the next compartment between cross ribs 14 and 15. This compartment will be filled until the level of the upper edge of the cross rib 15 is reached, whereupon it overflows into the lowermost compartment filling the same until the level of the upper end of the opening 20 is reached. Any additional water will then pass through the opening 20 and thence down the groove 18 dropping into the ashes in the ash pit.

Opening 20 making a free passage between the ash pit and the hot air heating chamber of the furnace, it is desirable that injurious gases from the furnace shall not pass through said opening from the ash pit to the air heating chamber. Various means for insuring against such gas passage may be used. In Figs. 1, 2, 3 and 4 one form of construction for this purpose is shown wherein the rib 15 adjacent the opening 20 is slightly increased in height and, integral therewith, a housing is cast comprising a top 21, sides 22 and an inner side or back 23 with an opening 24 at the lower edge of the back 23 whereby water in the lower compartment may pass into the interior of the housing and thence to the opening 20 for drainage. Any gases passing from the ash pit through the opening 20 are trapped within the housing thus made and cannot escape through the opening 24, as this opening is submerged at all times when there is water in the lower compartment of the water holding tray or receptacle.

Instead of making this housing structure integral with the tray it can be made as a separate member with a top 21^a, sides 22^a and inner side or back 23^a at the lower edge of which the opening 24^a corresponding to opening 24 in the structure shown in Fig. 4, is made. The top 21^a at its front edge is formed with a hook portion 25 to hook over the upper edge of the cross rib 15 as shown in Fig. 5. This to all practical intents and purposes provides a housing trap for gases from the ash pit which are trapped in the same manner as described with reference to Fig. 4.

It is evident that this construction shown in Fig. 5 may be applied to humidifiers wherein the side and cross ribs are cast integral with the upper side or top connecting the vertical sides of the ash pit forward extension. This is indicated in Fig. 6 where in the separable housing trap, identical with

that shown in Fig. 5 and heretofore described, is hooked over the rib 15^a cast integral with the inclined section 5 of the top to the ash pit forward extension; and of course the integral construction shown in Fig. 4 could be applied thereto quite as well.

In Fig. 7 a still further form of trap is shown wherein the water drained through the opening 20 passes into a goose neck 26 formed in a drain pipe 27 which lies below the part 5. This downwardly curved trap portion 26 in the pipe 27 is an old and well known means used for trapping against the passage of dangerous gases, being used to a large extent in plumbing to prevent the passage of sewer gases; and it works in the relation here described upon the same principle. However the constructions shown in Figs. 1 to 6 inclusive are preferred for the reason that this pipe 27, having a small passage therethrough, is liable to become plugged up, filling with sediment and thus stopping the drainage of water to the ash pit.

The water is supplied to the humidifier tray or receptacle through a spout 28, the inner end of which lies directly over the front compartment of the humidifier while the outer end extends through the front plate 7 in position so that water may be supplied continuously from any suitable source substantially as indicated in my application for patent to which reference has been made.

The construction described is very simple, economical to produce, easily applied by unskilled labor and has no parts to get out of order. The bulky water pan heretofore used with humidifiers is eliminated, a large evaporating surface is provided with a consequent greatly increased evaporation of water and dissemination thereof through the heated air passing from the furnace. The water is supplied continuously, the greater portion thereof being evaporated and such part as is not evaporated is drained into the ash pit moistening the ashes and eliminating all dust therefrom. This construction for furnaces installed and in use is particularly useful and has so proved in practice. The invention is defined in the appending claims and is to be considered as comprehensive of all forms of structure coming within their scope.

I claim:

1. In a furnace, an ash pit casting of substantially cylindrical form provided at its front side with an outwardly extending portion, comprising spaced apart vertical sides and a downwardly and inwardly inclined top connecting said vertical sides at their upper edges, said top having an opening therethrough, a tray formed with a downwardly and inwardly inclined bottom, and ribs cast integral therewith at its edges and extending upwardly, said tray resting on

the top of the forward extension to the ash pit casting, a boss on the under side of the bottom of the tray adapted to fit in the opening in said top of the ash pit extension, said boss and bottom of the tray having an opening therethrough, substantially as described. 70

2. In combination, an ash pit casting of substantially cylindrical form provided at its front side with an outward extension, comprising spaced vertical sides and a downwardly and inwardly inclined top connecting said vertical sides at their upper edges, said top having an opening therethrough between its uppermost and lowermost points, a tray comprising a downwardly and inwardly inclined bottom and vertical ribs integral with the bottom and extending upwardly therefrom at its edges, a boss formed integrally with the bottom of the tray at its under side adapted to pass 80 into the opening in the top of the ash pit extension, said boss and bottom having an opening therethrough, whereby when water reaches a predetermined level in the tray, the opening serves as a drainage passage for additional water to carry the same to the ash pit, and means associated with said opening into which water may pass for preventing the upward passage of gases from the ash pit into the space above the tray, substantially as described. 90

3. In a furnace, an ash pit casting of substantially cylindrical form provided at its front side with an outward extension, comprising spaced vertical sides and a downwardly and inwardly inclined top disposed between and cast integral with said sides, means whereby a limited quantity of water may be held at the upper side of said top, said top having an opening therethrough to drain excess of water into the ash pit, and means associated with said opening into which water may pass to prevent the passage of gases from the ash pit through the opening into the space above said ash pit forward extension, substantially as described. 100

4. In a furnace, an ash pit casting of substantially cylindrical form provided at its front side with an outward extension, comprising spaced vertical sides and a downwardly and inwardly inclined top integral with and connecting the upper edges of said sides, a water holding tray comprising a downwardly and inwardly inclined bottom and upwardly extending ribs at its edges located on the top of said forward extension to the ash pit, said tray and bottom having openings therethrough in conjunction with each other at points between the uppermost and lowermost points of said tray and bottom, and a housing over said opening in the tray comprising front and rear sides and spaced lateral sides and a top over said sides, said rear side of the housing being formed with an opening at its lower edge, substantially as described. 110

43

tially as and for the purposes described, and vertical ribs integral with and extending upwardly from the bottom at its edges; said substantially cylindrical form provided at its bottom of the tray having an opening there-
front side with an outward extension, comprising spaced vertical sides and a down-
wardly and inwardly inclined integral top, connecting the vertical sides at their upper
edges, said top having an opening there-
through between its uppermost and lower-
most points, a water holding tray comprising
a downwardly and inwardly inclined bottom;

5. In a furnace, an ash pit casting of sub- upwardly from the bottom at its edges; said substantially cylindrical form provided at its bottom of the tray having an opening there-
front side with an outward extension, comprising spaced vertical sides and a down-
wardly and inwardly inclined integral top, connecting the vertical sides at their upper
edges, said top having an opening there-
through in conjunction with the opening in 15
the top of the ash pit extension, and means
to continuously supply a predetermined
quantity of water to the tray, substantially
as described.

In testimony whereof I affix my signature. 20

OSCAR P. NYSTROM.
